INSULATED DRINKING CUP

Richard K. Shelby, 1145 Hickory Trail,
Downers Grove, Ill.

Filed Aug. 26, 1964, Ser. No. 81,448

Term of patent 14 years

(Cl. D44—9)

FIG. 1

FIG. 3

FIG. 2

I claim:

The ornamental design for an insulated drinking cup, as shown.
